WINDOW CONSTRUCTION

Waldo L. Kraemer, Brooklyn, N. Y., assignor to
 Kearfott Engineering Company, Inc., a corpora-
 tion of New York

Application December 8, 1936, Serial No. 114,755

2 Claims. (Cl. 114—178)

The invention herein disclosed relates to a window construction for a ship and in particular to a window construction that may form a unit in a glass-enclosed deck.

5 An object of the invention is to provide a window construction for the deck of a ship in the form of a unit which when used with a series of similar units forms in effect a glass-enclosed deck. Another object of the invention is to provide 10 a window construction of this type that may be opened and closed and which in the closed position is weathertight.

These and other objects of the invention and certain advantages thereof which will herein- 15 after appear are accomplished in accordance with this invention by providing a window frame that may be secured to spaced columns and the side of the ship and which has vertical sides and ends of substantial thickness. Each of the sides 20 of the window frame has a channel-shaped window-pane guideway extending longitudinally thereof at the transverse center. A window-pane frame is mounted in the window frame at one end thereof and on one side of the channel- 25 shaped guideways and another window-pane frame is mounted in the window frame at the other end thereof and at the opposite side thereof. The space between these window-pane 30 frames is closed by window-panes slidably mounted in the channel-shaped guideways.

Such a window is illustrated in the accompanying drawings in which:

Fig. 1 is a front elevation thereof;

Fig. 2 is the same on a smaller scale and illustrating the connection of the cables for operating the sliding window-panes;

Fig. 3 is a transverse sectional elevation taken along the line 3—3 of Fig. 1;

Fig. 4 is a fragmentary section taken along the line 4—4 of Fig. 1;

Fig. 5 is similar to Fig. 4 taken along the line 5—5 of Fig. 1; and

Fig. 6 is a fragmentary section taken along the line 6—6 of Fig. 1.

In the drawings there is illustrated a window construction for the deck of a ship that forms a unit. When several of these windows are secured to the side of a ship, they form a glass-enclosed deck. The unit shown in the drawings 45 consists of a frame 1 having integral end sections 1a and 1b and vertical side members 1c and 1d. The end and side members of the frame are of substantial thickness, of sufficient thickness to accommodate three panes of glass spaced laterally of each other, and have a lateral cir-

cumambient flange 1e at one edge. The sections of the flange 1e on the end cross members of the frame are secured to the side of the ship 2 and the sections of the flange on the side members 1c and 1d are secured to spaced columns 3 5 of T shape in cross-section, the flanges and the portion of the ship's side above the opening overlapping the frame opening somewhat as shown. The side frame members 1c and 1d have formed therein at substantially the transverse center 10 thereof, longitudinal channel-shaped guideways 1f. These guideways extend from the top to the bottom of the frame, and are defined on the inner faces of the frames by a ridge or boss along each side of the groove for a purpose presently to appear. 15

At the top of the window frame 1 there is mounted within the frame a window-pane frame 4 in which there is mounted a window-pane 5. The window-pane frame 4 is secured in position 20 in the window frame 1 between the outer boss and the overlapping flanges on the columns and ship's side by brackets 2a, and extends downwardly in the window frame approximately one-fourth of the length of the side members 1c and 1d. The lower cross member and the side members of the window-pane frame 4 are of H shape 25 in cross section and the upper cross member is of channel-shape in cross-section and the window-pane 5 is received in the channels, a flexible 30 material 6 such as rubber being placed between the window-pane and the window-pane frame. This window-pane frame 4 is mounted in the window frame 1 so that its outer surface is flush 35 with the outer surface of the window frame. A similar window-pane frame 7 is mounted in the window frame 1 at the lower end thereof and inwardly of the channel-shaped guideways 1f. As shown the outer edges of the side frames 1c and 1d are flanged inwardly to cooperate with the inner boss to provide a retaining channel for the frame 7. In the window-pane frame 7 there is a window-pane 8. The window-pane frame 7 extends upwardly of the window frame approximately one-fourth of the length of the vertical 45 sides 1c and 1d and it is secured to the window frame. The upper and side pieces of the frame 7 are substantially H-shaped in cross-section as clearly illustrated in Figs. 3 and 6. The upper cross piece of the frame 7 has a filler piece 9 and 50 a finishing piece 10 therein.

Within the channel-shaped guideways 1f there is mounted a pair of window-pane frames 11 and 12. The window-pane frame 11 carries a window-pane 13 and the window-pane frame 12 car- 55

- ries a window-pane 14. The frames 11 and 12 are slidably mounted in the channel-shaped guideways 17. The side members of these frames are substantially H-shaped in cross-section as shown in Figs. 4 and 5 and extend into the channel-shaped guideways 17. The channel-shaped guideways 17 are lined with felt 15 to make a weathertight connection between the channel-shaped guideways and the window-pane frames. The cross pieces of the window-pane frames 11 and 12 are channel shaped in cross-section. The lower cross piece 11a of the window frame 11 has an arcuate groove 11b formed therein and the upper cross piece of the window-pane frame 12 has an arcuate tongue 12a formed thereon which is received in the arcuate groove 11b when the window-pane frames are together. The window-pane frames 11 and 12 are shown in the closed position but they are slidable in the channel-shaped guideways from the position shown to a position in which the window-pane frame 11 is directly opposite the window-pane frame 4 and the window-pane frame 12 is directly opposite the window-pane frame 7 leaving an opening of substantially one-half of the length of the window frame.

The window-pane frame 11 carries handles 16 through which this window-pane frame may be raised and lowered. Cables 17 and 18 operating over pulleys 19 and 20 at one side of the frame and pulleys 21 and 22 at the other side of the frame connect the window-pane frames 11 and 12 so that these window-panes are moved simultaneously in opposite directions. The pulleys 19 and 20 are rotatably mounted in a bracket 23 mounted on the top of the window frame adjacent the side edge thereof so that the edge of the pulleys 19 and 20 extend over the edge of the side 1d of the frame. The pulleys 21 and 22 are mounted in a similar bracket 24 at the other end of the cross piece 1a. The cables 17 and 18 may be connected to the window-pane frames 11 and 12 in various ways that are well known in the art.

One method of connecting these cables to the window-pane frames is illustrated in Fig. 2 wherein the cable 17 is connected at one end to the upper edge of the window-pane frame 11. It then extends along the side 1c of the window-pane frame and over the pulley 21 to the pulley 19. It then extends down along the side 1d of the window-pane frame and is connected to the upper edge of the window-pane frame 12. The cable 18 is connected at one end to the upper edge of the window-pane frame 12 and extends along the side 1c of the window frame and over the pulley 22. From the pulley 22 it passes across the top of the frame to the pulley 20 and then down along the side 1d and is connected to the upper edge of the window-pane frame 11. In this arrangement, the weight of the window-pane frame 12 is depended upon for the lowering of this window-pane frame. It will thus be seen that when the window-pane frame 11 is raised through the application of a force on the handles 16, the part of the cable 17 attached to the upper edge of the window-pane frame 11 will be loosened by the amount the window is raised and will therefore permit the window-pane frame 12 to drop. Similarly, the cable 18 will permit the window-pane frame 12 to drop. When the windows are in the open position and the window-pane frame 11 is moved downwardly by application of force to the handles 16, the cables 17 and 18 following the window-pane frame 11 draw the

window-pane frame 12 upwardly until the two meet as shown in Figs. 1, 2 and 3.

On the upper edge of the window-pane frame 11, there is an L-shaped clamp 25 which secures weather-stripping 26 to the upper edge of the window-pane frame 11. This weather-stripping 26 extends from the outer edge of the window-pane frame 11 and wipes along the window-pane frame 4 and the window-pane 5 when the window-pane frame 11 is moved upwardly and downwardly. In the closed position the weather-stripping 26 forms a weathertight joint between the window-pane frame 11 and the window-pane 4. A similar clamp 27 secures a piece of weather-stripping 28 to the lower cross piece of the window-pane frame 12 and the weather-stripping 28 forms a weathertight connection between the window-pane frame 12 and the window-pane frame 7. It will be seen that with the arrangement illustrated the windows are in effect shingled. The window-pane frame 4 is outwardly of and overlaps the window-pane frame 11 and the window-pane frame 12 is outwardly of and overlaps the window-pane frame 7. The shingling effect is thus from the top to the bottom and provides for drainage, making it less likely for any leakage of water past the window when the window is in the closed position.

The window-pane frame 11 is secured in the closed position by two bolts 29 and 30. The bolt 30 29 is slidably mounted in a bracket 31 that is secured to the side 1c of the window-pane frame by screws 32 and 33. The bracket is hollow and the bolt is provided with a handle 29a and a pin 29b which extends through the bracket 31. Sur- 35 rounding the pin, there is a washer or collar 34 and between this collar and a shoulder 31a formed in the bracket 31 a spring 35 acts to force the bolt or pin 29b towards the window-pane frame 11. In the closed and locked position of 40 the window, the pin 29b of the bolt 29 extends into a hole formed in the upper cross member of the window-pane frame 11 as shown in Fig. 3. When it is desired to open the window, the bolt 29 is pulled so as to release the connection between 45 the pin and the window-pane frame. A pin 29c extending radially of the pin 29b is received in a slot in the bracket and when the bolt 29 is pulled against the action of the spring 35 the pin 29c will, upon rotation of the bolt, engage the edge of 50 the bracket and the pin 29b will be held out of the path of the frame 11. The bolt 30 is similar in all respects to the bolt 29.

For the purpose of forcing the window-pane frame 12 against the lower edge of the window-pane frame 11, there are provided two wedge elements 36 and 37. These wedge elements are mounted in brackets 38 and 39 that have flanges which are secured to the sides 1c and 1d of the window-pane frame. The brackets 38 and 39 extend along the upper cross piece of the window-pane frame 5 as shown in Fig. 1. The wedge-shaped elements are L-shaped as shown in Fig. 3 and are rotatably mounted in the brackets. The wedge-shaped element 36 is rotatably mounted in the bracket 38 on a pin 39 that extends through the bracket and the element 36, the pin being threaded into the bracket 38. As shown in Fig. 5, the wedge-shaped element 36 has an abutment 36a which when the element is rotated to the position shown in Figs. 1, 3 and 5, presses against the window-pane 14. When the element 36 is rotated to the left from the position shown in Fig. 5 the contact between the abutment 36a and the window-pane is released. The face of 75

the abutment 36a is slightly inclined and when it is moved to the wedging position, that is, the position shown in Fig. 5, it effects a force on the window-pane tending to raise the window-pane frame 12 thus causing a tight joint between the window-pane frames 11 and 12.

It will be obvious that various changes may be made by those skilled in the art in the details of the embodiment of the invention illustrated in the drawings and described in detail above within the principle and scope of the invention as expressed in the appended claims.

I claim:

1. A unitary window construction for the deck of a ship comprising, in combination with spaced columns having outer flanges flush with the ship's side above and below an opening, a window frame having a circumambient lateral flange secured around the opening to the inner faces of the said flanges and of the portions of the ship's side above and below the opening, the frame being so proportioned that the said flanges along the sides of the opening and the ship's side above the opening overlap the frame, the side members of the frame having each a centrally disposed longitudinal guide channel and an inwardly projecting retaining boss along each side thereof, an upper stationary window-pane frame secured in the frame at the top of the opening between the outer boss and the overlapping flanges and ship's side, a lower stationary window-pane frame secured in the frame at the bottom of the opening against the inner boss, and a pair of oppositely moving window-pane frames slidable in the guide

channel and proportioned to close the space between the upper and lower stationary window frames.

2. A unitary window construction for the deck of a ship comprising, in combination with spaced columns having outer flanges flush with the ship's side above and below an opening, a window frame having a circumambient lateral flange secured around the opening to the inner faces of the said flanges and of the portions of the ship's side above and below the opening, the frame being so proportioned that the said flanges along the sides of the opening and the ship's side above the opening overlap the frame, the side members of the frame having each a centrally disposed longitudinal guide channel and an inwardly projecting retaining boss along each side thereof, an upper stationary window-pane frame secured in the frame at the top of the opening between the outer boss and the overlapping flanges and ship's side, a lower stationary window-pane frame secured in the frame at the bottom of the opening against the inner boss, a pair of oppositely moving window-pane frames slidable in the guide channel and proportioned to close the space between the upper and lower stationary window frames, means connecting the movable pair of frames for effecting mutually opposite movement between them, and means carried by the lower stationary frame and operative upon the lower of the pair of frames to urge the two movable frames together.

WALDO L. KRAEMER.
